Inventor:

James P. Williams

Ames A. Harry

UNITED STATES PATENT OFFICE.

JAMES P. WILLIAMS, OF ST. LOUIS, MISSOURI.

BUILDING BRICK.

1,409,632.

Specification of Letters Patent. Patented Mar. 14, 1922.

Application filed August 10, 1921. Serial No. 491,173.

To all whom it may concern:

Be it known that I, JAMES P. WILLIAMS, a citizen of the United States, residing at St. Louis, in the State of Missouri, have invented 5 certain new and useful Improvements in Building Bricks, of which the following is a specification, reference being had therein to the accompanying drawing.

This invention relates to building-bricks 10 or blocks, and especially to what are generally known as "air-cell bricks" and also as "one-handed blocks;" and the invention comprehends a wall structure built of these bricks or blocks as well as the brick or block 15 itself.

It is an object of the invention to provide a building-brick of cellular form, and one which will possess maximum strength and be capable of convenient and economical 20 manufacture.

It is also an object of the invention to provide a brick which includes a plurality of air cells and, also, means disposed intermediate the cells for catching or receiving 25 moisture which may seep through the mortar-joint and for carrying the same away.

A further object of the invention contemplates the utilization of one of the cellular members—preferably the central one— 30 as a hand-hold in the handling of the bricks, whereby the weight of the brick is evenly distributed, making a balanced article when being handled by a workman.

The invention has other objects, of more 35 or less importance and advantage, all as will herein be made apparent from the following description.

In order that the invention may be readily understood, I have disclosed the same in the 40 accompanying drawings; but these are to be understood as merely illustrative of a preferred and practical embodiment, as the invention is susceptible of a wide range of modification and variation without departing 45 from its spirit or sacrificing any of its salient features or underlying principles.

In these drawings:

Figure 1 is a view in perspective of a single brick embodying my invention; and 50 Fig. 2 is a view in perspective of two bricks arranged in superposed relation, as when forming a part of a wall construction.

Referring to these drawings, the reference-numeral 1 designates, in general, one 55 of my improved "one-handed" bricks, the same being rectangular in form and of wall-

widthwise dimensions. In Fig. 2, two of these bricks are shown, one superposed upon the other and separated by a layer of mortar 2, as usual.

Each brick, preferably and as shown, includes two load-sustaining side-members 3, 3. These side members are so formed as to have their upper surfaces 4 and their lower surfaces or base-portions 5, respectively, lying 65 in common planes; that is to say, the upper surfaces 4 of the two side members are disposed in the same horizontal plane, as well as the two lower surfaces 5 being disposed 70 in the same horizontal plane.

Each load-sustaining member is formed with a longitudinally-extending air-cell 6, which may be of any required form or dimension. These cells extend the entire length of the brick and provide two of a plurality of air-conduits for each brick.

Extending between and connecting the load-sustaining members is a transverse horizontal web 7 which, with the base portions 5 of the load-sustaining members, constitutes the base of the brick.

For the purpose of providing a hand-hold and an additional air-cell, I have shown each brick as formed with two transverse connecting webs 8, 8, disposed above and parallel with the base-web 7, which connect with and outstand from the inner walls 9 of each load-sustaining member. Upstanding from these connecting webs are two side walls 10, 10, to which is connected an upper 90 transverse, horizontal web 11 disposed in the same plane with the top webs 4 of the load-sustaining members.

The walls 9 of the load-sustaining members, the webs 8, and the walls 10 form a 95 moisture-receiving channel 12 at one side of each of the load-sustaining members. It will be noted that the upper transverse web 11 is disposed in parallelism with the base-web 7, and that it is connected to the side-walls of the load-sustaining members above a plane passing through the centers thereof by what I shall hereinafter refer to as an angular web which includes the horizontal web 8 and the vertical web or wall 10. 105 These angular webs and the connecting upper-web 11 constitute a hand-hold disposed between the load-sustaining members so that these portions are balanced in relation to the hand-hold.

The base-web 7, the upper top web 11, the angular connecting webs, and portions

of the load-sustaining walls provide a central air-cell 13.

For wall and similar construction work, the bricks are preferably to be superposed one upon another, as shown in Fig. 2, a layer or course of mortar 2 being laid upon the upper surfaces 4 of each load-sustaining member. As thus arranged, the load-sustaining members occupy a position one above another with a layer of course of mortar spacing them apart.

By reason of the fact that the central top web 11 is, as aforementioned, in the same plane as the upper surfaces of the load-sustaining members and is not covered with mortar, it will be observed from Fig.

2 that, in constructing a wall of these bricks, there are but two mortar-contacting points, these being the upper surfaces 4 of the two load-sustaining members and the base-portions 5 of the superposed brick, so that there is provided an additional chamber or air-cell 14 formed by the lower surface of the base-web 7 and the upper surface of the top-web 11, this chamber being spaced from the mortar of the load-sustaining members by these moisture-receiving channels 12, and this construction and arrangement preclude any moisture that may seep through the mortar-joint 2 from passing beyond the channels 12. Thus, the chamber 14 constitutes a moisture-free space between each proximate brick.

I am aware that it has heretofore been proposed to provide bricks with so-called "interlocking webs" on their lower surfaces which are adapted to register with depressions in the subjacent brick and be secured therein by a layer of mortar; but such bricks in use have been demonstrated to be objectionable, in that there is but a slight unbroken mortar-joint, so that moisture seeping in will work across the brick and into the inner wall of the dwelling.

In herein referring to the building element as an "air-cell brick" or "one-handed block," I intend these terms to comprehend all building tiles which are adapted to be handled by the one hand of a workman. Ordinarily, these building elements vary in size from 8 inches long, 4 inches wide, and $\frac{1}{4}$ inches thick, to an element of the same length and thickness but of double width.

The term "brick" has been defined by the National Brick Manufacturers' Association as a body of burned clay or clay-matter, either solid or cored, of rectangular shape, and which measures approximately 8" x 4" x $\frac{1}{4}$." This size is known as the "brick standard." In increasing the measurements, either as to length, width or thickness, the article produced is termed a "block" or "tile." At the present time, the designation for a building element for wall-structure, in which the element as a single

unit extends from the face to the rear of the wall and is provided with air-cells therein, is "load-bearing building-tile." However, if this element is of such measurements that it can be handled by the one hand of a workman, it is designated "one-handed building-block" or "one-handed building-tile." Furthermore, if the element is adapted to withstand great crushing strength, it is also termed "load-bearing tile" in order to distinguish it from the non-load-bearing tile or what is commonly known as "fire-proofing tile." The average standard sized solid brick weighs about six pounds, while an "air-cell brick" (so-called) weighs about seven pounds.

From the foregoing, it will be perceived that the building-brick which comprises the present invention constitutes a simple and effectual means of meeting the advantageous and avoiding the disadvantageous features above set forth, and while it has been described and illustrated in the embodiment herein shown, it will be understood that I do not wish to limit myself to the precise form of this disclosure, as many changes in the construction and general arrangement of the parts may be made without departing from the spirit of the invention as set forth in the appended claims.

What I claim as new and desire to secure by Letters-Patent is:

1. A building-brick comprising load-sustaining members each provided with a longitudinally-extending air-cell and each having a base-portion, a lower horizontal transverse web connecting the base-portions of the sustaining members and constituting with said base-portions a base for the brick, an upper horizontal transverse web parallel to the base of the brick and spaced therefrom, and right-angular webs connected to the ends of the upper web and to the sustaining members; the angular and upper webs constituting a hand-hold between the sustaining members and balanced in relation to the sustaining members; the walls of the angular webs and sustaining members constituting moisture-receiving channels; all parts of the brick being included between the planes of the upper and lower surfaces of the sustaining members.

2. A building-brick comprising load-sustaining members each provided with a longitudinally-extending air-cell and each having a base-portion, a lower horizontal transverse web connecting the base-portions of the sustaining members and constituting with said base-portions a base for the brick, an upper horizontal transverse web parallel to the base of the brick and spaced therefrom, and angular webs connected to the ends of the upper web and to the side walls of the sustaining members; the angular and

upper webs constituting a hand-hold between the sustaining members and balanced in relation to the sustaining members; the walls of the angular webs and sustaining members constituting moisture-receiving channels; all parts of the brick being included between the planes of the upper and lower surfaces of the sustaining members.

3. A building-brick comprising load-sustaining members each provided with a longitudinally-extending air-cell and each having a base-portion, a lower horizontal transverse web connecting the base-portions of the sustaining members and constituting with said base-portions a base for the brick, an upper horizontal transverse web paralleling the base of the brick and spaced therefrom, and angular webs connected to the ends of the upper web and to the side walls of the sustaining members above a plane passing through the centers of the members; the angular and upper webs constituting a hand-hold between the sustaining members and balanced in relation to the sustaining members; the walls of the angular webs and sustaining members constituting moisture-receiving channels; all parts of the brick being included between the planes of the upper and lower surfaces of the sustaining members.

4. A building-brick comprising load-sustaining members each provided with a longitudinally-extending air-cell and each having a base-portion, a lower horizontal transverse web connecting the base-portions of the sustaining members and constituting with said base-portions a base for the brick, an upper horizontal transverse web paralleling the base of the brick and spaced therefrom, and angular webs connected to the ends of the upper web and to the side walls of the sustaining members; the angular and upper webs constituting a hand-hold between the sustaining members and balanced in relation to the sustaining members; the walls of the angular webs and sustaining members constituting moisture-receiving

channels; the walls of the upper and lower transverse webs, the angular webs and the portions of the sustaining members constituting a central air-cell; all parts of the brick being included between the planes of the upper and lower surfaces of the sustaining members.

5. A building-brick comprising load-sustaining members each provided with a longitudinally-extending air-cell and each having a base-portion, a lower horizontal transverse web connecting the base-portions of the sustaining members and constituting with said base-portions a base for the brick, an upper horizontal transverse web paralleling the base of the brick and spaced therefrom, and right-angular webs connected to the ends of the upper web and to the sustaining members; the angular and upper webs constituting a hand-hold between the sustaining members and balanced in relation to the sustaining members; the walls of the angular webs and sustaining members constituting moisture-receiving channels; all parts of the brick being included between the planes of the upper and lower surfaces of the sustaining members; the base-portion of the brick being continuous and uninterrupted.

6. A building-brick comprising side load-sustaining members, hollow throughout their length; a base-web connecting the members at their lower portions; top webs connecting the members between their upper and lower portions; a central mortar-joint breaking member spaced from the sustaining members; and a plurality of right angular channels formed in the upper portion of the brick between the central member and the sustaining members.

In testimony whereof I affix my signature in presence of two witnesses.

JAMES P. WILLIAMS.
